UNITED STATES PATENT OFFICE.

JOHN L. FERGUSON, OF JOLIET, ILLINOIS, ASSIGNOR TO THE QUAKER OATS COMPANY, OF CHICAGO, ILLINOIS, A CORPORATION OF NEW JERSEY.

ROTARY SHRINKER.

Application filed January 17, 1921. Serial No. 437,729.

To all whom it may concern:

Be it known that I, JOHN L. FERGUSON, a citizen of the United States, residing at Joliet, in the county of Will and State of

5 Illinois, have invented new and useful Improvements in Rotary Shrinkers, of which the following is a full, clear, concise, and exact description, reference being had to the accompanying drawing, forming a part of

10 this specification.

My invention relates to packaging machines and it has especial relation to machines of the character designated wherein package caps are fitted tightly upon package bodies by conforming means which operate upon the packages after the caps have been initially loosely placed upon the bodies.

More particularly my invention relates 20 to machines wherein the caps are shrunk unto, or made to conform to, the package bodies by enveloping the capped package, to a predetermined degree, by contracting means. While I will hereinafter 25 describe my machine as operating upon a package having a cap fitting down over the outside of the package body, it is to be understood that the machine may also function, as hereinafter described, when the cap is set inside of the body, and presents either 30 its convex or concave portion outwardly.

As will hereinafter appear, my machine embodies means which operate to so shrink the ends of packages that the tightening of 35 the caps, or the close conformation thereof to the package bodies, when said caps possess any of the above described characteristics, is within the purview of this invention. This matter will, however, be 40 more fully discussed in connection with the specific construction and operation of my machine.

Some difficulty has heretofore been experienced in accurately positioning very 45 tight fitting caps upon package bodies and this is particularly true with respect to packages made from paste-board or analogous materials. If the caps are made as tight fitting as may ultimately be desired, the time consumed, by such labor as is

usually employed on the assembly of these packages, in fitting such tight caps over the package bodies is somewhat excessive.

The usual practice, therefore, is to so construct the caps that they may be positioned 55 on the bodies without unduly forcing the operation. As a result the caps are somewhat loose-fitting and, although they do not fall off during the packing operation, their failure to fit the package bodies tightly does 60 contribute markedly to certain difficulties experienced when a sealing label is applied to the capped package to firmly secure the body and the cap portions together. In other words, when the caps are applied, as 65 they usually are in the present practice and not smoothed down or made to conform very closely with the body of the package, the sealing label which is subsequently applied must be subjected to a rather strenuous stretching and pressing process in order to pull the same into place and thereby 70 overcome the inequalities in package diameter which are occasioned by the application of loose caps to the package bodies. 75

It is one of the objects of my invention, therefore, to so operate upon the caps, after their initial positioning, that they are smoothed down and conformed accurately 80 to the body of the package whereby substantially no inequality between the diameter of the package body and that of the package cap is present. The sealing label may then be applied to the package without the necessity of smoothing or stretching 85 the same to properly secure the caps and package body together.

As I have above indicated, however, my process of shrinking and conforming the cap to the body portion of the package results in a very desirable tight fitting joint, irrespective of whether or not a label is thereafter applied to seal the cap and body together. As I will hereinafter point out, if the cap is of the internal character, my shrinking means will so operate upon the package that the cap and body are shrunk 95 together and a desirable tight joint formed therebetween.

Again, the specific form, which is utilized 100

in practicing my invention, embodies heating means for causing the contraction or shrinking of the package ends so that a tight fitting joint is obtained. I find that 5 the employment of heating means at this point in the packaging of materials, or in the making of sealed packages, is particularly advantageous in that the heat which is imparted to the package during the 10 shrinking process becomes a valuable adjunct when the sealing label is applied to the packages. It is the usual practice to apply the sealing label to the packages immediately after the caps have been positioned thereupon.

Moreover, it has been necessary heretofore to place the packages in a drier in order to cause the adhesive, which is used to secure the sealing label to the package, 20 to dry as rapidly as is necessitated by manufacturing considerations. When my improved machine, however, is employed at one point in the packaging of materials the need for drying the adhesive after application 25 of the label is eliminated. I find that the heat, which remains in the package after the shrinking process is employed, is sufficient to quickly dry the adhesive upon the label which is applied thereto. The temperature 30 of packages treated in accordance with my process is raised to such a point that the drying of the adhesive upon the sealing label is so facilitated that a substantial gain in time is made and the packaging process rendered substantially continuous 35 from the time of the filling of the packages until they are shipped, there being no need to subject the completed and sealed packages to a drying atmosphere.

Again, the use of a shrinking process to 40 firmly secure the caps to the package bodies does not necessitate a special treatment of the caps inasmuch as I treat the material, from which said caps are punched, with a substance 45 which prevents their sticking to the punching mechanism. The presence of this substance in the package walls renders the same shrinkable whereby it will be observed that I have utilized an element, 50 which is already necessarily present, to facilitate a desirable method of packaging whereby a substantially continuous process ensues.

Various other objects of my invention 55 will appear, and will be very fully described and pointed out, in the following description of the construction and operation of a machine embodying my invention.

For a better understanding of my invention 60 reference may be had to the accompanying drawings; in which,

Figure 1 is a perspective view of a machine embodying my invention and taken from one corner thereof;

Fig. 2 is likewise a perspective view of

the machine shown in Fig. 1, but taken from the diagonally opposite corner of said machine;

Fig. 3 is a side elevational view of the 70 machine;

Fig. 4 is an elevational sectional view taken on the line 4-4 of Fig. 3;

Fig. 5 is an elevational sectional view taken on the line 5-5 of Fig. 4;

Fig. 6 is a top plan view of the machine; 75

Fig. 7 is a fragmentary sectional view taken on the line 7-7 of Fig. 3;

Fig. 8 is a fragmentary view, partially in section, illustrating the manner in which an electrical connection in my machine is 80 effected;

Fig. 9 is a fragmentary view of another portion of my machine; and

Figs. 10 are fragmentary, sectional views 85 through the ends of packages illustrating the three ways in which caps may be positioned with respect to package bodies.

Referring more particularly to the drawings, I have shown, for convenience only, my machine as mounted upon a base 20. 90 Mounted on this base are standards 21-21 which have attached thereto journaled portions 22-22, a shaft 23 being supported between said portions 22.

Rigidly secured to the shaft 23 are plates 95 or disc-like members 24-24, the latter being perforated circumferentially thereof (as best shown in Fig. 9), in order to provide the mounting thereupon of sleeves 25. The sleeves 25 when so mounted extend through the openings in the plates 24 and provide bearing members whereby certain elements may be reciprocated perpendicularly through said plates. As shown, these sleeves have a flange 25* formed thereabout whereby the 100 sleeves themselves may be mounted normally to the plane of the plates 24. The outer edges of the plates 24 are formed to comprise gear teeth 26 whereby the plates comprise gear wheels, for purpose to be 110 hereinafter described.

Referring now to Fig. 4, the plates 24 are mounted in opposed relation upon the shaft 23 and it will be understood that the sleeves 25 are so mounted on the plates that they are paired, that is, those on one plate are perpendicularly opposite those on the other plate. Contracting or shrinking heads 27 have formed integrally therewith a hollow stem 28 which is adapted to slide axially along the sleeves 25. The heads comprise hollow-walled, cup-shaped members, an electrical resistance element 29 being disposed annularly about the inner wall 120 of the head 27.

A gripping head 30 is associated with each of the shrinking heads and it will be understood that, because of the positioning of the sleeves, heretofore pointed out, these gripping heads 30 and the cup-shaped 125

shrinking caps 27 on one plate are directly opposite the analogous elements on the other plate. A stem 31 is secured to the head 30 and is adapted to be supported in, and 5 slide axially of, the hollow stem 28 of the head 27, it being understood that the movements of the two stems are independent, one of the other, by reason of an apparatus hereinafter to be set forth. Moreover, it 10 should be observed that the head or gripping member 30 is of such dimensions that the caps 27 may pass thereover and envelop the heads 30.

Formed integrally with the journal portions 22 are annular members 32 which are, of course, stationary in character. Secured to, and supported by, these member 32 are annular cams 33, whose planes are substantially parallel to the planes of the plates 24, 20 but which are formed sinuously or offset, as shown, to cause a reciprocating movement of certain parts which are mounted perpendicularly thereto and are revolved circumferentially thereabout. Secured to the cams 25 33 are other cams 34 which are likewise annular in character and have offset portions for particular purposes. These latter cams are mounted outside of the cams 33 and may be formed integrally therewith, if so desired. 30 The sleeves 25 are slotted at 35 to permit of the extension of the cams 33 and 34 therethrough. It will be noted that this slotted portion is long enough to provide for the offset portions of the cams 33 moving therein without tending to move said sleeves.

The hollow stems 28 are recessed at 36 so that they fit snugly over the annular cam 33 while recesses 37 in the stems 31 fit over the cam 34. In order to prevent the turning of the stems 31 and the consequent disengagement of the recesses 37 and the cam 34, as well as to prevent the disengagement of the cam 33 with the recesses 36 by the turning of the hollow stems 28, pins 38 extend upwardly through longitudinal slots 28^b and 25^b cut in the stems 28 and the sleeves 25, respectively. This positioning of the pin 38 prevents the movement of the stems 28 and 31 in any direction except 50 axially of the sleeves 25.

As before pointed out, the cams 33 and 34 are stationary whereas the plates 24, together with the heads and sleeves mounted thereupon, are rotarily movable because of their positioning upon the shaft 23. It follows, therefore, that, when the stems 28 and 31 are rotated about the cams 33 and 34, the former will be reciprocated, because of the offset portions of the cams. In Fig. 4, 55 the shrinking caps and the gripping heads of the associated pair at the top of the figure are shown in their open position or that position in which said heads and caps are furthest from the center line of the drum formed by the opposed plates. If now the

drum is rotated the heads 30 will first be moved towards one another by reason of the engagement of the slots 37 with the cams 34. It will be observed that this movement is relatively slight, the extreme inward or 70 closed position of these heads being shown in the pair at the bottom of the figure. That is, the movement of these heads is just sufficient to grip the ends of an object which is placed therebetween. Considering now 75 the shrinking caps 27 and the manner in which they are moved by the engagement of the slot in the hollow stem 28 with the cam 34, it will be noted that the movement imparted to the heads 27 by the rotation of the plates 24 about the cam 33 is considerably greater than the movement imparted to the gripping heads 30 by the cam 34. The extreme inward position of these heads is likewise shown in the pair of elements at the 80 bottom of the figure and it will be observed that the heads have moved over and enveloped the gripping heads, whereby any object which is held between said gripping heads has the ends thereof surrounded by 85 two of the heated shrinking or contracting heads 27. The closed pair of heads at the bottom of the machine are shown as gripping a package which is being operated 90 upon. 95

In the drawing, I have illustrated the contracting heads as moving over the package ends in an enveloping manner only and thereafter contracting the caps by heat alone. Should it be desired to contract the 100 caps by physical contact with the contracting head, this may, of course, be arranged for by properly dimensioning the enveloping cap whereby it comes into contact with the package cap as it (the machine cap) is moved thereover and operates to physically iron down the cap onto the body of the package. 105

I will next describe the apparatus and mechanism whereby packages are conveyed 110 into the proper position to be gripped by the gripping heads 30 as well as that apparatus whereby the packages, after the caps have been shrunk thereupon are ejected, at 115 a predetermined point, from the drum formed by the plates 24.

Referring to Figs. 1, 3, 5 and 6 a pair of inverted U-shaped frames 39 are mounted upon the base 20 in such a way that they 120 substantially straddle the drum. Attached to the upper portions of these frames is one end of a conveyor 40 which comprises a chain 41 upon which are mounted triangular retaining members 42, the ends of the latter sliding along stationary angle irons 43, as best shown in Fig. 1. Guiding members 44 are positioned at the side of the conveyor and slightly above the carrying member 42 of said conveyor. It will be understood that 125 the packages, by reason of the inclination of 130

the conveyor, are carried upwardly by the triangular member 42. The ends of said packages are rolled along the irons 43 and are guided by the members 44.

- 5 Rollers 45—45 are so arranged that they press against the ends of packages which pass therebetween and thus operate to force the caps, which have been initially positioned, firmly unto the body portion of the 10 packages. At the same time, these rollers function to accurately predetermine the length of the packages which are supplied to the shrinking machine.

15 The highest point of the package conveyor is at 46. From this point the packages roll downwardly along the incline surface 47 and between guiding elements 48—48, finally coming in contact with a member 49 which shunts them downwardly toward the package 20 gripping heads, heretofore described. Mounted on the shaft 23 is a spider 50 which has formed, around the outer circumference thereof, a plurality of package cradling members 51 in the form of segments 25 of a cylinder. Referring to Fig. 5 it will be apparent that a package after being shunted downwardly by the member 49 will drop onto the spider and be cradled between two of the members 51. While so 30 cradled the package is accurately positioned with respect to the gripping heads, and it is further to be understood that the closing movement of the gripping heads takes place while the package is so cradled between two 35 of the members 51 at substantially the highest point of the drum.

40 The drum travels in a counter-clockwise direction as shown in Fig. 5 by the arrow. The packages are, therefore, carried from the top of the drum around to a point at the right hand side of the machine as shown in Fig. 5, whereby each package is retained in gripped and shrinking or contracting relation with the afore-described heads during 45 substantially three-fourths of the revolution of the machine drum.

45 The cams 42 and 43 are so related to the gripping heads and shrinking caps that the packages are released as they come to the point on the machine at which a guiding member 52 is positioned. When the packages are released the combined action of the members 51 and the rotation of the machine is such that the packages are ejected and forced to roll downwardly along a surface 55 52, as shown in Fig. 2. Another conveyor 53 comprising a chain 54 and the triangular pieces 55 attached thereto, then picks up the packages and conveys them away, 60 usually, as before intimated, to a labeling machine wherein a sealing label is wrapped about the package in such manner that the cap is sealed to package body. It may, of course, be desirable to allow the packages 65 to drop from the machine upon their release

by the gripping and shrinking heads, and I do not wish to limit myself, therefore, to the showing of the off-bearing conveyor 52 illustrated in Fig. 5. It is desirable, however, to maintain the packages in contact 70 with the shrinking heads during the longest feasible time and thereafter throughout as large a portion of the circumference of the drum as possible.

75 Referring now to the manner in which the shrinking caps are heated, it will be observed, particularly in Fig. 3, that the leads pass along a conduit 56 and are connected to a brush holder 57, the brush 58 in the latter bearing upon a slip-ring 59 which 80 is annularly disposed about a hub portion 60 by means of which one of the plates 24 is secured to the shaft 23. From the slip-ring 59 the leads 61 are carried to annular conduits 62 mounted on the sleeves 25. 85 From these conduits individual leads 63 are connected to each of the shrinking heads 27. A binding piece 64 being utilized to effect the connection between the leads 63 and resistance elements 29. The main leads are 90 carried through a conduit 65 from one plate to another as shown in Fig. 4, and the connections to the heads mounted on the plate opposite to that one which carries the slip ring are effected in a manner analogous to 95 that above described.

95 As a convenient means of driving the drum and associated conveying apparatus I have shown a motor 66 from which a belt 67 extends to a pulley 68, the latter being 100 mounted upon a shaft 69. A gear wheel 70 is pinned to the latter shaft and serves to drive a shaft 71 through a gear wheel 72. On the shaft 71 are keyed small gear wheels 73—73 which mesh with the teeth 26 formed on the outer circumference of the plates 24. The gear 26 meshes with a small gear 74 which, through bevel gearing 75, turns the rollers 45. At the same time a chain and sprocket connection 76 drives the conveyor 110 chain 41.

Having described a machine embodying my invention, the operation thereof and the manner in which a desirable continuity of production is obtained thereby, will now 115 be described.

120 As I have above indicated, the caps, or under some conditions, the body portions, of the packages are formed by punching and I so treat the material from which these package portions are formed that they do not tend to adhere to the forming mechanism. The material of these same portions is therefore rendered shrinkable. The caps are placed upon the package bodies and, 125 inasmuch as a tight fit is not provided for, no difficulty is experienced nor is an excessive amount of time consumed in loosely placing such caps upon the bodies. The packages are then placed upon their sides 130

on the conveyor 40 and are rolled upwardly therealong by the bearing of the pieces 42 against the packages. As the packages pass between the rollers 45 the caps are pressed 5 on and the length of the packages positively gagged.

It should be understood that in preparing caps, as is the usual practice, by punching, they may be more or less mutilated at times 10 or may not fit accurately. As the packages pass over the top of the conveyor 40 they are fed into the drum one by one by the guiding member 49 and are cradled on the portions 15 51 of the slowly rotating drum. The heads 30 are next moved inwardly and firmly grip the ends of the packages. The contracting or shrinking heads then move over the gripping heads and envelop the package ends to a degree determined by the amount the cams 20 33 is offset. These shrinking heads remain in the enveloping position during substantially three-fourths of the revolution of the drum and during this time the package ends are heated whereby the caps are contracted 25 or shrunk so that the excess diameter or slight mutilation thereof is, as it were, "ironed out" so that the cap conforms very closely, and is substantially equal in diameter, to the diameter of the body. This treatment 30 of the caps may be effected wholly by heat or the caps may be of such configuration that they serve to slightly press the cap edges against the body as they pass over the same. After the shrinking heads have been 35 maintained in enveloping relation with the packaging ends for substantially three-fourths of the revolution of the drum, the cam 33 so functions that the shrinking heads are withdrawn from said relation. Thereafter 40 the cam 34 operates to retract the gripping heads 30 whereupon the package is released and, because of the members 51 and the rotation of the drum, rolls out into the conveyor 53.

45 As I have above indicated, the temperature of the packages is being raised, during the shrinking process, to such a point that, when the sealing label is applied thereto, the adhesive upon said label dries very rapidly. 50 At the same time the package presents a smooth cylindrical surface by reason of the ironing-out process to which the caps have been subjected, whereby the sealing label may be applied thereto much as it would be 55 applied to a perfectly smooth surface. In other words, no stretching or smoothing of this label is now necessary because all of the surface inequalities, which have heretofore necessitated such stretching and pulling, 60 have been eliminated by the shrinking process.

From the above description of the operation of my machine it will be apparent that all of the desired operations which I have

set forth, are performed entirely automatically and by a machine wherein the automatic operations are accomplished with a minimum number of parts. As I have intimated hereinbefore, it is not necessary that a machine embodying my invention be limited 65 in its use to packages wherein the caps overlie the body portion or, in other words, wherein the lips of the caps are exterior to the bodies. 70

In Fig. 10, I have shown, in cross section, 75 a variety of ways in which caps may be associated with package bodies. The first diagram shown is that of a package such as I have hereinbefore discussed as operated upon in my machine. However, should this 80 cap be placed inside the body portion as illustrated in the second sketch, the operation of the machine would be just as effective, although it would not be necessary to employ gripping heads in this connection 85 since the cap portions would adequately retain and hold the packages during the shrinking process. Again, if the caps were inverted and the concave portion thereof presented outwardly, as indicated in the 90 third sketch, my machine would effect the desired shrinking operation and consequent tight joint inasmuch as, instead of the cap being shrunk inwardly onto the body, the body would be conformed to the cap. 95

Moreover, in the foregoing I have described the operation of my machine in connection with cylindrical packages but, it will be understood that the operation thereof is exactly the same if it is desired to shrink 100 caps on packages having other shapes, such as square packages. In any event, the shrinking caps are made to conform to the package caps whereby the latter are effectively shrunk. 105

In discussing my invention I have spoken of the machine as shrinking or compressing the package ends and the caps thereon to justify the outside diameters of the cap portion and of the body portion. From one 110 point of view, the body portion under the cap will, of course, be reduced as said cap is shrunk thereupon. It will also be apparent, that, if the body portion of the package is so operated upon that it is reduced or "necked-in" and a cap thereafter affixed thereto which has the same outside diameter as the outside diameter of the main body portion, a smooth surface will result. As above pointed out I so combine the package conforming operations that the cap is justified directly on the package body whereby a much simpler and efficient method of securing a smooth surface is realized. 115 120

Broadly speaking, therefore, it will be 125 seen that my invention contemplates two distinctly novel features. I have described, I believe, the first apparatus or method of

shrinking caps onto can bodies as distinguished from conforming caps to said bodies by utilizing mechanical pressure.

All of the prior art cap-conforming apparatus with which I am familiar makes use of some sort of forming device associated with a mandrel. It is obvious that a mandrel cannot be utilized when it is desired to cap both ends of a package and conform the caps thereto at the same time. As I have above pointed out this is one marked advantage which is obtained by the use of my invention. Inasmuch as the entire operation is carried on through the medium of heat or some other means not necessitating the actual mechanical contact of a pressing means against the package and cap, it is apparent that all of the difficulties which are inherent when a fragile material, such as most cans are composed of, is operated upon by a pressing means, are overcome.

Moreover, inasmuch as I believe myself to be the first to suggest the use of heat, or its equivalent, in this connection, I do not wish to limit myself to the simultaneous shrinking of caps and bodies, but desire protection for the use of heat alone to shrink can bodies.

In the necking-in machines which have heretofore been employed the same difficulties which are above mentioned as being present when caps are mechanically pressed onto cans are met with. If it should be desired to utilize heat or an equivalent shrinking medium to neck-in package bodies before they are capped, I wish it to be understood that such an operation comes within the purview of my invention; since, as I have pointed out, there does not appear to have been heretofore utilized any shrinking medium for accomplishing the reduction of the ends of can bodies.

In this particular connection I wish it also understood that while I have heretofore defined shrinking means as utilizing heat to effect the shrinking, I do not intend to limit myself to the use of heat if it should be hereafter discovered that shrinking can be accomplished through some other means. That is, I regard the essence of my invention as described, to be in the use of reducing means which operate without mechanical pressure against the cans, and for purposes of convenience I have designated such means as shrinking means and have described them as utilizing heat to perform the shrinking. If some other means should be hereafter advanced for performing the reduction of cans and caps without utilizing mechanical pressure and operate in the same manner as my means, which I have above designated as shrinking means, it is to be understood that such operation is within the purview of my invention.

The second broad aspect which will appear as novel from the above description, is the reduction of the can body, or the smoothing out of the end-to-end surface thereof after the package is capped. This is a distinct departure in the art, since it has been usual heretofore either to first neck-in the can body and then apply a cap to it, or endeavor to form the cap upon the can body simultaneously with a reduction in the end of said body. This latter method of operation results in a cap having a lip which is wedged-shaped in cross section, such cap interfitting with a complementary wedged-shaped end of the package body. I am aware of the existence of machines for accomplishing the latter operation but do not consider such method at all analogous to that obtainable with my machine, nor does the wedged-shaped interfitting of the package end and cap eventuate the same character of capped package. In view of the above remarks with respect to my belief that I am the first to propose the reduction of the package ends after the package has been capped, I wish it understood that I am claiming the same broadly.

Finally, it will be observed, from the above description, that a new article of manufacture is obtained which comprises a capped package having the outside transverse dimensions of the cap and the body portion so equalized that an unbroken or uniplanar surface extends from end to end of said package and permits the wrapping of a label thereabout without necessitating the pulling and stretching of said label to prevent wrinkling of the same.

While I have illustrated but one machine embodying my invention it is obvious that many modifications therein may occur to those skilled in the art and I desire, therefore, that the same be limited only by the showing of the prior art and by the scope of the appended claims.

Having thus described my invention, what I claim as new and desire to secure by Letters Patent is:

1. A rotary drum and a plurality of capped-package shrinking devices associated therewith.

2. In a machine, package gripping means, and heat radiating shrinking means operating on the packages while carried by the gripping means.

3. In a machine, means for receiving and retaining capped packages, and means for shrinking the caps on said packages while so retained.

4. In a machine, means for pressing the caps toward the body portion of the package, and means for thereafter shrinking said caps tightly on said body portion.

5. In a machine, a rotary drum, a plu-

- rality of shrinking heads mounted thereon, gripping heads positioned within said shrinking heads and adapted to move independently thereof, means for initially pressing 5 the caps onto the bodies as the packages enter said drum whereby the length of the packages fed to said drum does not exceed a predetermined dimension, means for opening and closing said gripping heads to receive and discharge a package, means for moving 10 said shrinking heads over the caps and for retaining the same in said position during a predetermined travel of said drum, and means for heating said shrinking heads.
- 15 6. In a machine, a rotary drum, a plurality of shrinking heads mounted thereon, gripping heads positioned within said shrinking heads and adapted to move independently thereof, means for opening and closing 20 said gripping heads to receive and discharge a package, means for moving said shrinking heads over the caps and for retaining the same in said position during a predetermined travel of said drum, and 25 means for heating said shrinking heads.
7. In a machine, shrinking means, and means for automatically positioning said shrinking means over the capped ends of packages.
- 30 8. In a machine, shrinking means, and means for automatically positioning said shrinking means for a predetermined time over the capped ends of packages.
9. In a machine, shrinking means, means 35 for automatically positioning said shrinking means over the ends of packages, and means for releasing and ejecting said shrunk packages from said machine.
10. In a machine, cap adjusting means, 40 and means operating to shrink the caps on the packages after said adjustment.
11. In a machine, cap adjusting means, means operating to shrink the caps on the packages after said adjustment, and means 45 for ejecting the packages from said machine after the caps have been shrunk thereupon.
12. In a machine, shrinking means, and length determining means for a capped package acting upon said packages prior to 50 the functioning of said shrinking means.
13. In a machine, shrinking means, package holding means, and means for causing said shrinking means to envelop, to a predetermined degree, said package.
- 55 14. In a machine, means for conforming the cap portions of packages to the body portions thereof, and means for feeding capped packages to said first means.
15. In a machine, a plurality of means 60 for conforming the cap portions of packages to the body portions thereof, and means synchronized with said first means for feeding capped packages to the latter at the proper times.
- 65 16. In a machine, means comprising a plurality of contracting means arranged about a circumference for conforming the cap portions of packages to the body portions thereof, and means for feeding capped packages to consecutively positioned contracting means. 70
17. In a machine, means for conforming the cap portions of packages to the body portions thereof, means for feeding capped packages to said first means, and means for causing said conforming means to move into registry with said supply means at predetermined times. 75
18. In a machine, means comprising a plurality of contracting means for conforming the cap portions of packages to the body portions thereof, means for supplying packages to said first means, and means for moving said contracting means successively into registry with said supply means. 80
19. In a machine, a member adapted for rotary movement, means mounted on said rotary member and comprising a plurality of contracting means for conforming the cap portions of packages to the body portions thereof, means for supplying packages to said first means, and means for moving said contracting means successively into registry with said supply means. 85
20. In a machine, means comprising a plurality of contracting means for conforming the cap portions of packages to the body portions thereof, means for supplying packages to said first means, means for moving said contracting means successively into registry with said supply means, and means for independently moving said contracting means into operative relation with the packages as fed. 90
21. In a machine, means comprising a plurality of contracting means for conforming the cap portions of packages to the body portions thereof, means for supplying packages to said first means, and means for setting said contracting means to permit the association of packages therewith, for bringing said means into operative relation with the packages, and for again moving said means to release one package and receive another. 95
22. In a machine, a movable member, contracting means mounted on said member, and means comprising a stationary member cooperating with the contracting means to cause the latter to properly act upon packages fed to the machine. 100
23. In a machine, a rotary drum, a plurality of contracting means mounted on said drum, and a stationary cam-like member cooperating with said means to move them into and out of operative relation with packages fed to said machine. 105
24. In a machine, a rotary drum, a plurality of contracting means mounted on said drum, and a stationary cam-like member 110
- 115
- 120
- 125
- 130

- cooperating with said means to move successive contracting means reaching a predetermined point in the travel of said drum into position to receive a package and for 5 releasing said packages at another point.
25. In a machine, means for receiving capped packages, contracting means for conforming the caps to the body portions of the packages, and means for moving said 10 contracting means from the point of receipt to a delivery point during said conforming process.
26. In a machine, a plurality of means for receiving capped packages, contracting 15 means for conforming the caps to the body portions of the packages, and means for so moving said contracting means that there is a continuous movement of packages from the point of receipt to a delivery point during 20 the contracting process.
27. In a machine, means for continuously progressing capped packages from one point to another, and contracting means operating on said packages during said movement. 25
28. In a machine, means for continuously progressing packages from one point to another, means for moving said packages about a circumference during said movement, and means for acting on said packages to conform the caps thereupon to the body portions during said circumferential movement whereby the latter operation is performed without affecting the continuity 30 of movement of the packages from point to point.
29. In a machine, means for continuously progressing packages from one point to another, means for moving said packages about a circumference during said movement, comprising gripping means arranged 35 by pairs, one means of each pair being mounted on opposed members, the package being fed to said means at a predetermined point on said circumference, and means for acting on said packages to conform the caps thereupon to the body portions during said circumferential movement whereby the latter operation is performed without affecting the continuity 40 of movement of the packages from point to point.
30. In a machine, a supporting frame, a drum mounted for rotation on said frame, package cap contracting means mounted on 45 said drum, means for so moving said drum that said contracting means are brought successively to a point of capped-package supply, and means associated with said drum to assist in positioning the packages in proper relation to said contracting means.
31. In a machine, a supporting frame, a drum mounted for rotation on said frame, package-contracting means mounted on said drum and adapted for movement substantially 50 perpendicular thereto to grip and act on packages, and stationary means cooperating with the contracting means to move the latter into gripping and operative relation with packages.
32. In a machine, a supporting frame, a 70 drum mounted for rotation on said frame, package-contracting means comprising package gripping means and shrinking heads mounted on said drum and adapted for movement normal to the plane of the drum, 75 a stationary cam member for controlling the time and extent of movement of said gripping means and shrinking heads, and means operatively connecting said cam member and said gripping means and shrinking 80 heads.
33. In a machine, a supporting frame, a drum mounted for rotation on said frame, package contracting means comprising package gripping means and shrinking heads 85 mounted on said drum and adapted for movement normal to the plane of the drum, and stationary cam members operatively associated with said gripping means and shrinking heads to cause the grippers to 90 first engage a package placed therebetween and to thereafter position said shrinking heads to operate on said package.
34. In a machine, a frame, a drum comprising opposed disk or plate members 95 mounted on a shaft journalled in the frame, means comprising gripping and shrinking heads mounted on, and adapted for movement normal to, said plates, said heads being secured to stems extending through the 100 plates, and cam means cooperating with said stems to cause the grippers to first engage a package placed therebetween and to thereafter position said shrinking heads to operate on said package. 105
35. In a machine, a frame, a drum comprising opposed disk or plate members mounted on a shaft journalled in the frame, means comprising gripping heads positioned within, and moving independently of, enveloping members, both the enveloping members and heads being provided with stems extending through said plates, and cams cooperating with said stems upon the movement of the drum to move said enveloping members and heads in proper sequence as dictated by the receipt or ejection of a package from said machine. 110
36. In a machine, a frame, a drum comprising opposed disk or plate members 115 mounted on a shaft journalled in the frame, means comprising gripping heads positioned within, and moving independently of, enveloping members, both the enveloping members and heads being provided with stems extending through said plates, cams cooperating with said stems upon the movement of the drum to move said enveloping members and heads in proper sequence as dictated by the receipt or ejection of a package from said machine. 120
37. In a machine, a frame, a drum comprising opposed disk or plate members 125 mounted on a shaft journalled in the frame, means comprising gripping heads positioned within, and moving independently of, enveloping members, both the enveloping members and heads being provided with stems extending through said plates, cams cooperating with said stems upon the movement of the drum to move said enveloping members and heads in proper sequence as dictated by the receipt or ejection of a package from said machine. 130

package from said machine, and means associated with said drum for holding said received package in proper position to be gripped and for assisting in ejecting said package when the same is released.

37. In a machine, a frame, a drum comprising opposed disk or plate members mounted on a shaft journalled in the frame, means comprising gripping heads positioned within, and moving independently of, enveloping members, both the enveloping members and heads being provided with stems extending through said plates, cams cooperating with said stems upon the movement of the drum to move said enveloping members and heads in proper sequence as dictated by the receipt or ejection of a package from said machine, and means comprising package cradles to position the incoming packages while they are gripped by the heads, said cradle members being mounted on said shaft.

38. In a machine, a frame, a drum comprising opposed disk or plate members mounted on a shaft journalled in the frame, means comprising gripping heads positioned within, and moving independently of, enveloping shrinking members, both the shrinking members and heads being provided with stems extending through said plates, cams cooperating with said stems upon the movement of the drum to move said shrinking members and heads in proper sequence as dictated by the receipt or ejection of a package from said machine, and a member mounted on said shaft intermediate of said plates and formed to comprise cradles cooperating with each pair of heads for holding said received package in proper position to be gripped and for assisting in ejecting said package when the same is released.

39. In a machine, a frame, a drum comprising opposed disk or plate members mounted on a shaft journalled in the frame, means comprising gripping heads positioned within, and moving independently of, enveloping shrinking members, both the shrinking members and heads being provided with stems extending through said plates, and cams cooperating with said stems, upon the movement of the drum, to move said shrinking members and heads toward the interior of said drum at predetermined points in the travel of the latter to cause said heads to grip a package placed therebetween and to cause said shrinking members to envelop, to a predetermined degree, said package.

40. In a machine, a frame, a drum comprising opposed disk or plate members mounted on a shaft journalled in the frame, means comprising gripping heads positioned within, and moving independently of, enveloping shrinking members, both the enveloping members and heads being provided

with stems extending through said plates, and cams cooperating with said stems upon the movement of the drum to move said enveloping members and heads toward the interior of said drum at predetermined points in the travel of the latter to cause opposed heads to bear against opposite ends of a package to hold the same, and at the same time, admit of the enveloping package ends by said shrinking means.

41. In a machine, a frame, a drum comprising opposed disk or plate members mounted on a shaft journalled in the frame, a plurality of sleeves mounted on said plates, contracting means comprising a portion fitting, and adapted to slide, in said sleeves, gripping means having a portion sliding within said contracting means, and a cam member engaging both said gripping and said contracting means.

42. In a machine, a frame, a drum comprising opposed disk or plate members mounted on a shaft journalled in the frame, a plurality of sleeves mounted on said plates, contracting means comprising a cap and a hollow stem attached thereto, said stem sliding in said sleeve, gripping means comprising a head and a stem sliding within said hollow contracting-means stem, and a cam having two directive surfaces, one engaging the contracting-means stem and the other engaging the gripping-means stem to move said caps and heads toward the center of said drum, for the purpose described.

43. In a machine, a frame, a drum comprising opposed disk or plate members mounted on a shaft journalled in the frame, a plurality of sleeves mounted on, and having axes substantially normal to, said plates, contracting means comprising a cap and a hollow stem attached thereto, said stem sliding in said sleeve, gripping means comprising a head and a stem sliding within said hollow contracting means stem, and a cam having two directive surfaces, said sleeves being apertured to receive said cams while said stems fit over and are moved by said cams, when said drum is given a rotary motion.

44. In a machine, a frame, a drum comprising opposed disk or plate members mounted on a shaft journalled in the frame, a plurality of sleeves mounted on said plates, contracting means comprising a cap and a hollow stem attached thereto, said stem sliding in said sleeve, gripping means comprising a head and a stem sliding within said hollow contracting-means stem, and cams comprising concentrically disposed annular members, and planes of which are substantially parallel to the plane of said plates, one engaging the contracting-means stem and the other engaging the gripping-means stem to move said caps and heads toward

the center of said drum, for the purpose described.

45. In a machine, a frame, a drum comprising opposed disk or plate members mounted on a shaft journalled in the frame, a plurality of sleeves mounted on said plates, contracting means comprising a cap and a hollow stem attached thereto, said stem sliding in said sleeve, gripping means comprising a head and a stem sliding within said hollow contracting means stem, cams comprising concentrically disposed annular members, the planes of which are substantially parallel to the plane of said plates, one engaging the contracting-means stem and the other engaging the gripping-means stem to move said caps and heads toward the center of said drum, for the purpose described, and means precluding the disengagement of the cams and the stems.

46. In a machine, a frame, a drum comprising opposed disk or plate members mounted on a shaft journalled in the frame, a plurality of sleeves mounted on said plates, contracting means comprising a cap and a hollow stem attached thereto, said stem sliding in said sleeve, gripping means comprising a head and a stem sliding within said hollow contracting means stem, cams comprising concentrically disposed annular members, the planes of which are substantially parallel to the plane of said plates, one engaging the contracting-means stem and the other engaging the gripping-means stem to move said caps and heads toward the center of said drum for the purpose described, and means comprising a pin attached in the gripping-head stem and extending through slots in the cap stems and said sleeves to prevent the movement of said stems in any direction except axially of the sleeves and in the plane of the slot whereby the disengagement of the cams and the stems is precluded.

47. In a machine, a frame, a drum comprising opposed plate members mounted on a shaft, means for driving said plates to rotate said drum, means mounted on said plate to hold and operate on packages while said drum is rotated, means for supplying packages to said drum, means adapted to bear against the ends of packages so supplied to gage the length thereof, and means governed by the relative rotation of said drum for moving said mounted means into operative relation with said packages.

48. In a machine, a frame, a drum comprising opposed plate members mounted on a shaft, means for driving said plates to rotate said drum, means mounted on said plate to hold and operate on packages while said drum is rotated, conveyor means for supplying packages to said drum, rollers at the side of said conveyor to bear against the ends of packages passing along said

conveyor to press caps on the packages, and means governed by the relative rotation of said drum for moving said mounted means into operative relation with said packages.

49. In a machine, a frame, a drum comprising opposed plate members mounted on a shaft, means for driving said plates to rotate said drum, means mounted on said plate to hold and operate on packages while said drum is rotated, conveyor means for supplying packages to said drum, rollers at the side of said conveyor to bear against the ends of packages passing along said conveyor, means for driving said rollers at the same speed as that at which the packages are moved by said conveyor whereby the caps are pressed into the bodies but no transverse movement of the former is caused and means governed by the relative rotation of said drum for moving said mounted means into operative relation with said packages.

50. In a machine, a frame, a drum comprising opposed plate members mounted on a shaft, means for rotating said drum, means for feeding packages to said drum, means mounted on said plates to hold and operate on the packages fed, means for initially positioning said packages upon entry to the drum to allow them to be properly gripped, and means cooperating with said last named means whereby the packages are ejected from the drum when released.

51. In a machine, a base, shaft supporting members mounted thereupon, a drum mounted on a shaft journalled in said members, inverted U-shaped members mounted on said base and straddling said drum, and conveyor means attached to said U-shaped members.

52. In a machine, a base, shaft supporting members mounted thereupon, a drum adapted to receive packages mounted on a shaft journalled in said members, inverted U-shaped members mounted on said base and straddling said drum, conveyor means attached to said U-shaped members, and guide members for directing the packages supplied by the conveyor to the proper point within said drum.

53. In a machine, a base, shaft supporting members mounted thereupon, a drum mounted on a shaft journalled in said members, said drum comprising means for contracting portions of packages fed thereto, inverted U-shaped members mounted on said base and straddling said drum, conveyor means attached to said U-shaped members for supplying packages to said drum, and means for moving said drum to successively present contracting means to a package as the latter is supplied by said conveyor.

54. In a machine, a base, shaft supporting members mounted thereupon, a drum

- mounted on a shaft journalled in said members, said drum comprising heating means for contracting portions of packages fed to said drum, means for supplying heating current to each of said means comprising a main conduit, individual leads to each contracting means, and a slip ring contact. 5
55. In a machine, a base, shaft supporting members mounted thereupon, a drum comprising opposed plates mounted on a shaft journalled in said members, said drum comprising electrical heating means for contracting portions of packages fed to said drum, an annular conduit mounted on each 10 plate to carry wires, leads therefrom to each of said contracting means, a slip ring connected to said conduits, and a brush bearing on the latter and connected to a source of supply. 15
56. A shrinking cap comprising a cup-shaped member and heating means associated with said member for contracting an article positioned therewith. 20
57. A shrinking cap comprising a hollow-walled cup-shaped member and heating means positioned within said wall. 25
58. A shrinking cap comprising a hollow-walled cup-shaped member and heating means comprising an electrical resistance member. 30
59. Means for holding and contracting packages comprising a shrinking cap and a gripping member adapted to be moved independently of said cap, the latter member being positioned within the concave portion of said cap. 35
60. Means for holding and contracting packages comprising a shrinking cap and a gripping member adapted to be moved independently of said cap, the latter member comprising a plate adapted to be protruded beyond said cap to bear against the end of a package which has been moved into position transversely of the cap face, the 40 cap being adapted to thereafter move over and envelop a portion of the package. 45
61. The method of closing a package which comprises applying a shrinkable cap thereto and thereafter shrinking said cap onto the package body. 50
62. The method of closing a package which comprises applying a shrinkable cap thereto and thereafter shrinking said cap onto the package body by the application of heat alone. 55
63. The method of closing a package which comprises applying a shrinkable cap thereto, shrinking said cap onto the package body, and thereafter applying a sealing label to said package whereby the adhesive upon the label is dried by the heat imparted to the package during the cap shrinking process. 60
64. The method of facilitating the closure of capped packages which consists in ini- 65
- tionally treating the material from which the caps are punched with a substance which precludes their adherence to the punching mechanism and, at the same time, renders said caps shrinkable, applying said caps to package bodies, shrinking said caps to conform to the package bodies, and, at the same time, heating said package, and thereafter applying a sealing label to said package whereby the adhesive upon the latter is dried rapidly by said heated package. 70
65. The method of facilitating the closure of capped packages which consists in initially rendering shrinkable the material from which the caps are made, applying said caps to package bodies, heating the capped packages whereby said caps are closely fitted thereonto and thereafter utilizing the heat imparted to said package to dry the adhesive upon labels applied to said packages. 80
66. The method of equalizing the outside transverse dimensions of a body package portion and a cap package portion to cause the finished capped package to present a smooth, end-to-end, surface which comprises simultaneously reducing the end of the body portion and a cap portion fitted on said end of the body. 85
67. The method of equalizing the outside transverse dimensions of a body package portion and a cap package portion to cause the finished capped package to present a smooth, end-to-end surface which comprises placing a cap on said body portion and thereafter reducing the package end so that the outside transverse dimension of the cap is equal to the outside transverse dimension of the main body portion. 90
68. The method of equalizing the outside transverse dimension of a body package portion and a cap package portion to cause the finished capped package to present a smooth, end-to-end surface which comprises placing a cap on said body portion and thereafter reducing the body under said cap and simultaneously reducing said cap so that the ultimate outside transverse dimension of said tightly fitting cap is equal to the outside transverse dimension of the main body portion. 105
69. The method of equalizing the outside transverse dimensions of a body package portion and a cap package portion to cause the finished capped package to present a smooth, end-to-end, surface which comprises placing a cap on said body portion and shrinking said cap and the end of the body thereunder so that the ultimate outside transverse dimension of said tightly fitting cap is equal to the outside transverse dimension of the main body portion. 110
70. In a machine for operating on capped packages, reducing means for so justifying the outside diameter of the cap portion and 115

the body that the outside surface of the package, from end-to-end, is uni-planar.

71. The method of conforming caps to a package whereby a smooth end-to-end surface of the capped package is obtained which consists in capping a package box and thereafter reducing the package ends to obtain said conformation.

72. The method of conforming caps to the body portion of capped packages whereby a smooth end-to-end completely capped

package is obtained which consists in initially capping the package box and thereafter reducing both the cap and the end of the package body under said cap whereby said conformation is obtained. 15

In witness whereof, I have hereunto subscribed my name.

JOHN L. FERGUSON.
